UNITED STATES PATENT OFFICE.

HOWARD L. WADSWORTH, OF CLEVELAND, OHIO.

SAND-CUTTING MACHINE.

1,849,988.

Specification of Letters Patent. Patented Aug. 17, 1920.

Application filed December 12, 1919. Serial No. 344,415.

To all whom it may concern:

Be it known that I, HOWARD L. WADSWORTH, a citizen of the United States, and a resident of Cleveland, county of Cuyahoga, and State of Ohio, have invented a new and useful Improvement in Sand-Cutting Machines, of which the following is a specification, the principle of the invention being herein explained and the best mode in which I have contemplated applying that principle, so as to distinguish it from other inventions.

The present improvements, relating to sand cutting machines, are more particularly directed to a machine of this general type constructed for manual propulsion over a floor and through a pile of sand to be cut and mixed. At present the only machines in use for cutting and mixing molding sand for foundries are large and expensive machines and are adapted for use in large foundries only, with the result that the saving which can be effected by the use of such machines is entirely lost to all of the smaller foundries, who are compelled to cut and mix their sand by hand.

The chief object of the present invention is the provision of a relatively cheap and light machine which can be used for smaller foundries and can be propelled by one or two men, who pull it through a pile of sand which is to be cut. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of the various mechanical forms in which the principle of the invention may be used.

In said annexed drawing—

Figure 1 is a side elevation of my improved machine; and Fig. 2 is a plan view of the same.

In Fig. 2 I have shown the machine as consisting of a forked framework, in which two side members 1 and 2 are mounted upon traction wheels 3, and are then curved into the form shown in Fig. 2, and combined to form a single handle 4. Each of the side frame members 1 and 2 are directed inwardly after passing the wheels 3 and are provided with two vertical forks 5 and 6, within which are mounted shafts 7, carry-

ing a series of vertical blades 8 and constituting a sand-cutting cylinder. There are thus two vertically arranged sand cutting cylinders mounted at a considerable distance from the axis of the wheels 3 and thus adapted to be raised and lowered toward the ground by raising or lowering the handle 4, and in this way the elevation of the cutting cylinders may be varied as conditions require.

Mounted upon the members 1 and 2 is a suitable source of power, such as an electric motor 10, connected by means of a driving chain or belt 11 to a transversely extending horizontal shaft 12 mounted in the upper frame members 5, and connected by means of bevel gears 13 and 14 to the vertical shafts 7, which drive the cutting cylinders. It is intended that the machine will be pulled over the ground and over and through a pile of sand in the direction indicated by the arrow A, with the cutting cylinders revolving toward each other, as indicated by the arrows A' on Fig. 2. Steel plates 15 are mounted on each side of the frame between the wheels and extend rearwardly to a point aligned with the center of the sand-cutting cylinders for directing the sand into the path of movement of these cylinders.

The direction of rotation of the sand-cutting cylinders may be reversed to drive these cylinders in directions opposite the arrows on Fig. 2, in which case the sand will be delivered at high speed against the side plates 15, which will either stop the movement of the sand or direct it in a direction opposite to the movement of the machine, in this way leaving the sand pile of the same width as the distance between the plates 15.

Similarly, the direction of movement of the machine may be reversed, that is, it may be pushed instead of being pulled, in which event the cylinders might best be operated in the directions opposite to the arrows, to give the same action as is obtained when the machine is operated in accordance with the arrows A and A'.

This improved machine can be built at a relatively low cost, since it consists primarily of nothing but a frame carrying the two cutting cylinders, and a motor, and is adapted for all small foundries where the cost of a larger and more complicated machine is out of the question.

Other modes of applying the principle of

my invention may be employed instead of the one explained, change being made as regards the mechanism herein disclosed, provided the means stated by any of the 5 following claims or the equivalent of such stated means be employed.

I therefore particularly point out and distinctly claim as my invention:—

1. In a machine of the character described, the combination of a frame, a pair of supporting wheels therefor, a rotary sand-cutting element mounted on said frame on one side of the axis of said wheels, and a handle attached to said frame on the other 15 side of said axis from said cutting element.

2. In a machine of the character described, the combination of a frame, a pair of supporting wheels therefor, a rotary sand-cutting element mounted on said frame 20 on one side of the axis of said wheels, a motor connected to operate said element, said motor being mounted on said frame on the other side of such wheels' axis from said element and thereby assisting to counter-balance the same, and a handle attached 25 to said frame for propelling the same.

3. In a machine of the character described, the combination of a frame, a pair of supporting wheels therefor, a rotary sand-cutting element mounted on said frame 30 on one side of the axis of said wheels, a

motor connected to operate said element, said motor being mounted on said frame on the other side of such wheels' axis from 35 said element and thereby assisting to counter-balance the same, and a handle attached to said frame and extending longitudinally thereof at one side of said frame.

4. In a machine of the character described, the combination of a frame, a pair 40 of supporting wheels therefor, a rotary sand-cutting element mounted on said frame on one side of the axis of said wheels, said frame comprising two side members mounted on said wheels, said members then being 45 joined and extended as one member serving as a propelling handle for said member.

5. In a machine of the character described, the combination of a frame comprising two spaced side members having adjacent end portions converging toward each other, and said members then being joined at their other ends and extended as one handle member, supporting wheels mounted in said frame members, two vertical sand-cutting cylinders mounted at the converging 50 end portions of said frame members, and a motor mounted on said frame and connected to operate said cylinders.

Signed by me, this 9th day of December, 60
1919.

HOWARD L. WADSWORTH.
